DESIGN FOR A LIGHTING FIXTURE

Charles A. Duepner, Minneapolis, Minn., assignor
to Branham, Mareck & Duepner, Inc., Minne-
apolis, Minn., a corporation of Minnesota

Application November 9, 1946, Serial No. 134,639

Term of patent 3½ years

(Cl. D48—4)

To all whom it may concern:

Be it known that I, Charles A. Duepner, a citizen of the United States, residing at Minneapolis, in the county of Hennepin and State of Minnesota, have invented a new, original, and ornamental Design for a Lighting Fixture, of which the following is a specification, reference being had to the accompanying drawing, forming part thereof.

Referring to the drawing:

Fig. 1 is a perspective view of a lighting fixture showing my new design;

Fig. 2 is a fragmentary top plan view thereof;

Fig. 3 is a front elevational view of Fig. 2;

Fig. 4 is a bottom plan view of Fig. 2; and

Fig. 5 is an end elevational view of Fig. 2.

I claim:

The ornamental design for a lighting fixture, as shown.

CHARLES A. DUEPNER.
